UNITED STATES PATENT OFFICE.

RAMON SENAC, OF MADRID, SPAIN.

RECEPTACLE OR PACKAGE OF COMPRESSED PAPER AND METHOD OF AND MEANS FOR MAKING THE SAME.

1,023,764.

Specification of Letters Patent. Patented Apr. 16, 1912.

Application filed May 27, 1911. Serial No. 629,848.

To all whom it may concern:

Be it known that I, RAMON SENAC, a subject of the King of Spain, residing in Madrid, in the Kingdom of Spain, have invented 5 certain new and useful Improvements in Receptacles or Packages of Compressed Paper and Methods of and Means for Making the Same, of which the following is a specification.

10 This invention relates to receptacles or packages of compressed paper, and intended to contain solid products, which will avoid the defects of those at present in use.

15 The invention also relates to a method of and means for making the receptacles.

For some time past the use of paper for the manufacture of resistant receptacles has been tried, and in some cases with success. Small flasks and bottles capable of wide application, are in existence, and also some 20 larger types, principally in Germany; but these articles are not of paper properly speaking, but of cardboard or pasteboard, with ends and hoops of wood, and nails are 25 used to close them. Such receptacles are expensive owing to the materials and cost of manufacture, and they are also heavy relatively to their capacity.

According to this invention, paper only 30 is used in the form of strips or bands, which are united by an adhesive and the receptacle is molded and compressed to the required shape and strength in suitable molds.

The invention will be understood from the 35 following description reference being had to the accompanying drawings, in which—

Figure 1 is an elevation of the receptacle and its lid; Fig. 2, a sectional elevation of the mold for the receptacle; Fig. 3 is a horizontal section on the line A—B of Fig. 2; Fig. 4 is an elevation of the portion of the mold, marked C—D in Fig. 3, showing the means for connecting the two parts of the mold; Fig. 5 is a section on the line E—F 45 of Fig. 4; Fig. 6 is an elevation and plan of the bottom of the mold; Fig. 7 is an elevation, partly in section, of the complete pressing apparatus; Fig. 8 is a section on the line G—H of Fig. 7; Fig. 9 is a section 50 on the line I—J of Fig. 7 showing the pressing chamber and its accessories in plan; and Figs. 10 and 11 sectional views of the die and the mold for making the lid.

An example of a finished cylindrical receptacle or package and its lid or cover,

made from compressed paper in the manner hereinafter described is illustrated in Fig. 1. The complete receptacle comprises two pieces, the body or receptacle proper and the lid, which are formed respectively with 60 integral projections or lugs 1 and corresponding recesses adapted to engage and interlock after the manner of a bayonet joint. These interlocking members are formed at various points on the periphery of the lid 65 and mouth of the receptacle, and the arrangement is such that the receptacle may be securely closed by putting on the lid and giving it the fraction of a turn. The receptacle shown has its external walls molded 70 with annular ridges 2 to simulate hoops, which give great strength to the receptacle.

For molding the cylindrical receptacle, a metallic mold 3 is used having a detachable bottom, which can also be of metal or of 75 a wood not affected by moisture. The construction of the mold is shown in Figs. 2—6. The mold is formed of two equal parts 3^a and 3^b, which are connected at their edges by hooked catches 4 attached to one half of the mold and adapted to engage in the other half. These catches 4 are countersunk in recesses in the side of the mold, as shown in Fig. 5. The bottom of the mold 80 inside has projections or ledges 5 to support the wooden bottom 6. The internal walls of the mold are, of course, shaped to mold the closing members and the "hoops" 85 on the receptacle.

7 denotes lugs for lifting purposes as will 90 be hereinafter explained.

The mold for the lid is similar to that for the body of the receptacle.

The bottom of the mold being placed in 95 position in the mold, and the two part mold closed and secured by the catches 4, it is now ready, and the method of making the receptacle will now be described.

The receptacle is formed from strips of 100 paper of any suitable nature coated with a suitable adhesive, and these strips are applied to the inner surface of the mold and superposed and intercrossed until the necessary thickness is obtained according to the strength which it is desired the receptacle 105 shall have. The adhesive is applied by a brush to the strips of paper, the length and width of which are determined at the discretion of the workman according to the 110 part of the mold to which they are to be ap-

plied, and then these adhesive strips are applied by hand to the internal walls and bottom of the mold. After the receptacle is molded, it must be compressed to give it 5 the necessary strength and insure the correct formation and rigidity of the closing members. Simultaneously during this pressing the greater part of the water in the adhesive is expressed. After the pressing, 10 which is effected in a press and in the manner hereinafter described, the receptacles are dried in suitable drying chambers.

The pressing apparatus illustrated in Figs. 7 to 9 comprises a strong metallic vessel or chamber 8, bolted to the pedestal or platform 9. During the pressing operation the mold with the receptacle in its interior is introduced into this chamber 8. The chamber 8 has its internal walls channeled as at 8^a, corresponding with other grooves in the base, to permit the escape of air when the mold is lowered into the chamber, which it fits very closely. The pressing chamber 8 at the top is enlarged to form 20 a seat for its lid 10. The inner periphery of the top of the said chamber is provided with an interrupted thread 11, adapted to engage with a corresponding thread on the lid 10, so that the lid can be secured in position by giving it a fraction of a turn. 25 Connected with this lid is a vessel 12, of rubber or other suitable material capable of expanding when air, water, steam, or other fluid under pressure, is injected into its interior, and the elastic vessel is the medium by which pressure is applied to mold and compress the receptacle.

13 denotes a metallic core between which and the rubber vessel an annular space 14 is 30 left into which the pressure fluid is introduced.

The lid 10 is suspended from a cross-bar 15 by a bolt 16 which permits it to turn, and the crossbar at its ends is adapted to 45 embrace and slide on guides 17 on the columns 18. The crossbar 15 is supported by a cable 19, which passes over guide pulleys 20 and 21, one of which 20 is located vertically over the point of suspension, and 50 the cable is wound up on a drum operated by worm gearing 22 and crank handle 23. To facilitate the raising and lowering operation, an additional cable 24 is provided which supports the counter-weight 25. The 55 cross-bar 15 also carries, at points equidistant from the center, tongs 26, suspended by chains and turning in a horizontal plane. The tongs are adapted to hold the mold by pairs of lugs 7 formed in the edges of the 60 mold, which lugs fit into recesses 27 of corresponding shape in the walls of the pressing chamber when the mold is in position therein.

When the lid 10 has been applied and the 65 chamber 8 is hermetically and securely

closed, the cock 28 is opened, which puts the interior of the elastic vessel 12 into communication with the pressure fluid. The elastic vessel is expanded by the pressure fluid to the form of the mold and strongly 70 presses the molded article on the inner walls and bottom of the mold (which is protected by the external resistant chamber 8), thus insuring an intimate connection of the paper strips and the correct formation and 75 rigidity of the receptacle and its closing members. At the same time the greater part of the liquid in the adhesive is expressed.

The sequence of operations in using the 80 apparatus is as follows:—The lid 10 with the elastic vessel 12 is raised to such a height as to permit the mold 3 and the receptacle in its interior to be placed below it and centered therewith. The lid and elastic vessel 85 are now lowered so as to introduce the elastic vessel into the mold, and enable the tongs 26 to take hold of the lugs 7 of the latter. The lid, elastic vessel and mold are then lowered until the mold rests on the 90 bottom of the pressing chamber 8, whereupon the tongs are released from the lugs 7, and by giving them a half turn they remain hanging outside the pressing chamber 8. The lid 10 is then fully lowered until its 95 thread 11 contacts with the thread of the chamber 8, when by giving the lid a part of a turn the respective threads are engaged and the closure effected. The elastic vessel 12 is then put into communication with the 100 pressure fluid by opening the cock 28, the pressure being ascertained by a manometer 29. On the completion of the pressing operation, the cock 28 is closed, and the operations are repeated in inverse order.

The compression of the lid, molded in a metal mold with a wooden bottom identical in arrangement with that for the body of the receptacle, is also effected at a single operation by pressing or stamping. For this purpose the mold shown in section in Fig. 10 is inserted into a very strong ring 30 of iron, steel or other metal, cut through its diameter and provided with a closing means operated by an eccentric lever. In the internal periphery of this ring are arranged pieces 31 the section of which is straight in the part in contact with the cylindrical part of the molded lid and conical inward. On these pieces is supported a conical die 32 with projecting flanges and the whole is compressed by a plate actuated by a hydraulic press, or by a screw, lever or other suitable means. On commencing the pressing, the die bears on the pieces and these compress the molded lid on the mold supported in the metallic ring, and the die is heated so that on completing its stroke the cylindrical surface of the lid and its top are compressed. On the completion of the press- 115 120 125 130

ing operation the ring is opened, and the die and the pressed lid removed, and the latter taken to the drying chamber.

No claim is herein made to the means for forming the lid or cover for the receptacle, but the same is shown and described for the purpose of making a complete disclosure, said subject-matter being reserved for a separate application.

10 I declare that what I claim is:—

1. A method of making receptacles or packages of compressed paper, which consists in applying strips of paper coated with an adhesive to the interior of a mold until the desired thickness is obtained, and molding and compressing the article in the mold by fluid pressure acting through the intermediary of an elastic pressing member.

2. In a method of making receptacles of compressed paper by pressing and molding strips of adhesive paper in a mold, the use of an elastic pressing member which is inserted into said mold and is formed of a material capable of being expanded by the pressure fluid so as to adapt itself to the internal configuration of the mold and transmit the pressure to the article to be molded.

3. A mold for producing receptacles or packages of compressed paper, which mold is made in two parts provided with countersunk hooked catches for securing the mold halves together, and also provided with a double bottom supported on projections near the bottom of the mold, and with two-part lugs for lifting purposes.

4. An apparatus for compressing and molding receptacles or packages of compressed paper, comprising a pressing cham-

ber, a lid for said chamber, means for securing the lid thereon in a fraction of a turn, an elastic vessel carried by said lid, a core secured to the lid so as to leave an annular space between the elastic vessel and the core, means for supplying pressure fluid to said annular space, and means for raising and lowering the lid and its appurtenances.

5. An apparatus for compressing and molding receptacles or packages of compressed paper, comprising a pressing chamber shaped to receive the mold, air-escape grooves on the internal walls of said chamber, a lid to close the pressing chamber, interrupted threads on the engaging surfaces of the lid and chamber so that the closure can be effected in the fraction of a turn, an elastic vessel carried by the said lid and capable of expanding to transmit the pressure to the article being compressed, a core secured to the lid so as to leave an annular space between the elastic vessel and its core, pipes and controlling means for supplying pressure fluid to the said annular space, a cross-bar revolvably connected to said lid, tongs pivotally connected to the cross-bar, uprights on which the cross-bar can slide up and down, and counterweighted cables and gearing for raising and lowering the cross-bar and its appurtenances.

In witness whereof, I have hereunto signed my name this 11 day of May 1911, in the presence of two subscribing witnesses.

RAMON SENAC.
